UNITED STATES PATENT OFFICE.

JULIUS SCHMOHL AND ERNST LAUSCHKE, OF CHICAGO, ILLINOIS, ASSIGNEES
TO BARNHART BROTHERS & SPINDLER, OF SAME PLACE.

DESIGN FOR A FONT OF PRINTING-TYPE.

SPECIFICATION forming part of Design No. 19,775, dated April 22, 1890.

Application filed January 2, 1890. Serial No. 335,687. Term of patent 14 years.

To all whom it may concern:

Be it known that we, JULIUS SCHMOHL and ERNST LAUSCHKE, both subjects of the Emperor of Germany, residing at Chicago, county 5 of Cook, and State of Illinois, have invented and produced a new and original Design for a Font of Printing-Type, which is fully set forth in the following specification, reference being had to the accompanying typographical 10 impressions, forming a part thereof.

This design comprises capitals, character &, figures, and points. In general style it is somewhat grotesque, quite extended, and each of its letters and characters has both light and heavy 15 lines in strong contrast, the light lines being hair-lines and the heavy lines quite uniformly heavy throughout the entire length of all straight lines, curved lines being swell-shaded from hair-lines to the full width of the heavy 20 straight lines.

The design is further particularly characterized by the form of capital B, which has both the bows parabolic in form, the upper bow having its lower line produced obliquely 25 to about the middle point of the stem, and the lower bow having its upper line in like manner produced obliquely in a direction which would meet the upper end of the stem, which causes it to meet the lower line of the 30 upper bow nearly at right angles about midway in the length of said line, and at a considerable distance, therefore, from the stem. A further characteristic is found in capital

K, which has the upper oblique element a hair-line throughout, except at the very extremity, the upper portion being curled over toward the right, forming a semicircular drooping hook. Another characteristic is shown in the letter J, which has its stem heavy and slightly expanded at the lower 35 end at the point where the curved portion takes off from the stem, producing the appearance of a stunted ceriph. Capitals P and R exhibit another characteristic, their ovals being about three-quarters of a circle, 40 whereby they seem to droop from the point of connection to the stem, said ovals extending considerably more than half the height of the letter.

A characteristic which is prevalent throughout the design is that the hair-lines deviate slightly from straight lines, being either 45 slightly bowed or slightly circumflex.

We claim—

The design for a font of printing-type herein 50 shown and described.

In testimony whereof we have hereunto set our hands, in the presence of two witnesses, at Chicago, Illinois, this 27th day of December, 1889.

JULIUS SCHMOHL.
ERNST LAUSCHKE.
